UNITED STATES PATENT OFFICE.

JOHN FISHER, OF PHILADELPHIA, PENNSYLVANIA, ASSIGNOR TO LORENZO W. NYE AND WILLIAM F. WAIT, OF AUBURN, NEW YORK.

DESIGN FOR CARPETING.

Specification forming part of Design No. 7,469, dated June 2, 1874; application filed May 22, 1874.
[Term of Patent 3½ years.]

To all whom it may concern:

Be it known that I, JOHN FISHER, of the city and county of Philadelphia and State of Pennsylvania, have invented and produced a new and original Design for Carpets, of which the following is a specification:

The nature of my design is fully represented in the accompanying photographic illustration, to which reference is made.

I claim as my invention—
The configuration of the design hereunto annexed, when applied to carpeting.

JOHN FISHER.

Witnesses:

LEMUEL GRANT,
Wm. NEILL.
